(57) **CLAIM**

The ornamental design for a chair, as shown and described.

DESCRIPTION

FIG. 1 is a perspective view from the front side of a chair.

FIG. 2 is a perspective view from the rear side thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The portions of the chair shown in broken lines are for the purpose of showing environmental structure only and form no part of the claimed design. The backrest sheet of the chair is made of mesh and the mesh pattern of the backrest sheet forms no part of the claimed design.
